BOWLING TETHERBALL GAME BOARD

Joseph J. Prischak, 3508 Zimmerly Road; Terry W. McQuaid, 4236 Feidler Drive; and Dennis J. Prischak, 3508 Zimmerly Road, all of Erie, Pa. 16506

Filed June 25, 1971, Ser. No. 157,078

Term of patent 14 years

Int. Cl. D21—01

U.S. Cl. D34—5 BB

Fig. 2.

FIG. 1 is a perspective view of the bowling tetherball game board according to the invention;

FIG. 2 is a perspective bottom view of the bowling game base.

The characteristic feature of our design resides in the particular mast configuration shown in combination with the base.

We claim:

The ornamental design for a bowling tetherball game board, as shown and described.
